INVENTOR
BURNITTA C. NEELY

Charles E. Townsend
ATTORNEY

UNITED STATES PATENT OFFICE.

BURNITTA C. NEELY, OF SACRAMENTO, CALIFORNIA.

DESIGN FOR A DOLL.

60,157.

Specification for Design.

Patented Jan. 3, 1922.

Application filed February 24, 1920. Serial No. 360,994. Term of patent 7 years.

To all whom it may concern:

Be it known that I, BURNITTA C. NEELY, a citizen of the United States, residing in the city of Sacramento, county of Sacramento, and State of California, have invented a new, original, and ornamental Design for a Doll, of which the following is a specification, reference being had to the accompanying drawings, forming a part thereof.

Fig. 1 is a view in perspective of a doll showing my new design.

Fig. 2 is a view in front elevation of a doll showing my new design.

Fig. 3 is a view in rear elevation of a doll showing my new design.

I claim—

The ornamental design for a doll, as shown.

BURNITTA C. NEELY.

Witnesses:

Mrs. M. NEELY,
SILVEY PEARLE TINSLER.
